UNITED STATES PATENT OFFICE.

GEORGE T. PEARSONS, OF NEW YORK, N. Y.

FIRE EXTINGUISHER.

Application filed January 6, 1919. Serial No. 279,096.

To all whom it may concern:

Be it known that I, GEORGE T. PEARSONS, a citizen of the United States, residing in the borough of Manhattan, city, county, and 5 State of New York, have invented new and useful Improvements in Fire Extinguishers, of which the following is a specification.

This invention relates to syringes to be used as fire extinguishers, in which a stream 10 or jet of liquid is ejected from a reservoir by pump mechanism within the reservoir, and it is the object of the invention to provide improved means to at all times connect the piston chamber with the liquid in the 15 lowermost part of the reservoir to discharge the liquid whether the reservoir is full or partially empty, or held in a horizontal position or inclined upward or downward from the horizontal.

20 In the drawing accompanying and forming a part of this specification Figure 1 is a longitudinal sectional view taken on the line 1—1 of Figure 2 with certain portions exaggerated to more clearly bring out the 25 invention; and

Figure 2 is a cross sectional view taken on the line B—B of Figure 1.

In the embodiment of my invention illustrated in the drawing there is provided a 30 reservoir or tank for a fire extinguishing liquid having a portion 3 of circular form in cross section, and which for convenience is termed as a liquid carrying chamber, and having an extension of reduced width along 35 one side thereof, as shown at 4, in which the pumping mechanism is located, to be adjacent the side wall of the reservoir. Ends 5 and 5' are secured to the body portion as by soldering or otherwise, the end 5 having 40 a discharge outlet 6 and a filler opening closed by a plug 7, the plug being constructed with an inwardly opening and outwardly closing spring check valve to permit entrance of air to the reservoir as the liquid is discharged therefrom. The end 5 may be 45 dished to permit of the standing of the syringe upon a horizontal surface.

As stated, the pumping mechanism is 50 mounted in the portion 4 of the reservoir, and is substantially of the same construction as that disclosed in my co-pending application filed June 28, 1916, Serial No. 106,322, the piston chamber comprising a cylinder 8 to which heads 9 and 9' are connected having inlets 10 and 11 with check 55

valves 12 and 13 opening into and closing outward from the piston chamber to connect the piston chamber with the liquid carrying portion of the reservoir. The piston chamber is connected to and extends from the end 60 5' of the reservoir substantially midway thereof and is connected to the outlet 6 by a chamber 14 which is in the nature of a compression chamber. A tube 15 slidably engages in a stuffing box 16 in the end or head 65 9 and through a cap 17 into a hollow piston rod 18, such cap 17 being secured to and closing one end of the piston rod and to which the tube is fixed. The piston rod extends through a stuffing box 20 to the exterior of the reservoir and has a hand grip 21 fixed thereto, said stuffing box being carried by a nut 22 which also serves to connect the piston chamber to the reservoir end 5' in a manner to be hereinafter set forth. 75

A piston head 23 having a suitable packing is mounted on the piston rod 18 to have a limited to and fro movement between the cap 17, which is in the nature of an abutment, and an abutment or collar 24 fixed 80 upon the piston rod. The piston rod is connected to the piston chamber through ports 25 therein controlled by the piston 23 to alternately connect the piston rod and the tube 15 with the piston chamber at opposite 85 sides of the piston at the commencement of each outward and inward stroke of the piston, and for which purpose the opening in the piston is made of somewhat larger diameter than the piston rod to provide a 90 space between the two, and communication between said space and the piston chamber is shut off by cone-shaped portions 26 and 27 on the abutments co-operating with correspondingly shaped seats in the ends of the 95 piston. The tube 15 is preferably located centrally of the chamber 14 with the outlet 6 offset from the center of said chamber, a tube 28 being connected to the outlet to connect the latter to the chamber 14. The tube 100 28 is of less diameter than the tube 15 and the outlet 6 restricted to create pressure in the chamber 14 and thereby increase the force of the ejected stream. To seal the pumping mechanism to prevent leakage 105 when the syringe is not in use, there is connected to the stuffing box 16 a tube 29 connected to the chamber 14 by ports 30 and in which tube 29 the outlet end of the tube 15 slidably engages. The tube 29 carries a 110

spring influenced valve 31 to engage with the end of the tube 15 when in its innermost position. The piston mechanism is locked in its innermost position with the end of the tube 15 closed by the valve 31 by a projecting portion or pin 32 on the piston rod co-operating with a cam slot 32' in an annular extension of the nut 22.

The valved inlets 10 and 11 to the piston chamber are located in extensions 33 and 34 of the respective heads of the piston chamber, and to maintain the pumping mechanism outside of the circumference of the circular or liquid carrying chamber of the reservoir, the piston chamber is so mounted that these extensions will lie adjacent the side wall and ends of the reservoir, as clearly shown in Figure 2 of the drawing. To at all times connect the piston chamber with the liquid in the lowermost part of the liquid carrying chamber, the inlet extension 34 which lies contiguous to the reservoir head 5' has a portion 35 to extend into the liquid carrying chamber and has an opening 36 in line with the axis of said chamber. A tube 37 having lateral ports 38 is fixed in said opening 36, and a tube 39 to extend longitudinally of the liquid carrying chamber with its ends lying adjacent the side and opposite ends of said chamber is mounted upon the tube 37 by a T coupling 40 to rotate around said tube 37. The T coupling has a portion of greater diameter than the tube 37 to provide an annular chamber with which the tube ports 38 communicate, as shown at 41. The T coupling is retained on the tube 37 by a flanged plug 42 connected to the end of the tube and suitable gaskets or packing are interposed between the ends of the coupling and said plug and the portion 35 of the extension 34 of the head 9' of the piston chamber. The inlet 10 is connected to the intake tube 39 by a pipe 43 connected at one end with the inlet 10 through extension 33 of head 9 of the piston chamber and connected at the other end to the extension 34 of inlet 11. It will be obvious that as the pumping mechanism is outside of the internal diameter of the liquid carrying chamber, that no matter in what position the syringe may be held horizontally, the intake tube 39 may revolve about the tube 37 and is adapted to automatically assume variable positions in the liquid in the reservoir near the side which is lowermost and so arranged with relation to the pumping mechanism as not to be obstructed in its rotative movement by the pump mechanism.

To connect the pumping mechanism with the liquid in the lowermost part of the reservoir with the discharge end of the syringe tilted upward or downward from the horizontal, valve mechanism is provided to automatically shut off the inlet to the tube 39

which is uppermost from the tube 37 and connect the lowermost inlet to the tube 39 thereto, said valve mechanism comprising a pair of valves 44 to co-operate with valve seats connected to or formed in the ends of the tube 39, said valves being connected by a rod 45 of greater length than the tube 39 so that when one of the valves is seated the other will be unseated.

Having thus described my invention, I claim:

1. In a syringe, the combination of a reservoir having an outlet; pumping mechanism mounted in fixed position in the reservoir contiguous to the side wall of the reservoir, said pumping mechanism having a suction inlet and an outlet connected to the reservoir outlet; and an intake tube extending longitudinally of the pump connected to said suction inlet revolvably supported and constructed and arranged to circumscribe a complete circle in its movement in that part of the reservoir not occupied by the pumping mechanism.

2. In a syringe, the combination of a reservoir having an outlet; a piston chamber supported in a fixed position in the reservoir at the side thereof and connected to the reservoir outlet and having a suction inlet; a piston to reciprocate in said chamber; and an intake tube extending longitudinally of the reservoir connected to the suction inlet and supported to have revolving movement through a complete circle without participating movement of the pumping mechanism and uninterrupted in its movement by the pumping mechanism in all positions thereof, for the purpose specified.

3. In a syringe, the combination of a reservoir having an outlet; a piston chamber located at the side of the reservoir and connected to the reservoir outlet, said chamber having suction inlets adjacent opposite ends; a piston to reciprocate in said chamber; an intake connected to the suction inlets having inlets from opposite ends of the reservoir; and means to revolvably support said intake to have movement through a complete circle, for the purpose specified.

4. In a syringe, the combination of a reservoir having an outlet; a piston chamber supported in a fixed position in the reservoir and connected to the reservoir outlet, said chamber having suction inlets adjacent opposite ends; piston mechanism to draw liquid through the suction inlets to opposite ends of the piston chamber and discharge said liquid through the reservoir outlet; a tube extending longitudinally of and with its ends adjacent opposite ends and the side of the reservoir; and means to connect said tube in fluid connection with the suction inlets of the piston chamber and support the tube to revolve through a complete circle independent of any participating movement of the piston chamber.

ber and the suction inlets thereto for the purpose specified.

5. In a syringe, the combination of a reservoir having an outlet; a piston chamber located at the side of the reservoir; suction inlet means for the piston chamber leading to opposite ends thereof and having an inlet at one side of the piston chamber and adjacent an end of the reservoir; and an intake 10 revolvable through a complete circle in fluid communication with said inlet of the suction means and having inlets from opposite ends of the reservoir, for the purpose specified.

6. In a syringe, the combination of a reservoir having an outlet comprising a cylinder having an extension of reduced width along one side thereof; pumping mechanism immovably mounted in said reduced portion of the reservoir connected to the reservoir outlet and having an inlet port; and an intake tube to said port revolvable through a complete circle in the reservoir, for the purpose specified.

7. A syringe comprising a cylinder having an extension of reduced width along one side thereof; a reciprocable piston cylinder pump immovably mounted in said extended portion of the reservoir and connected to the reservoir outlet and having a part extending laterally into the portion of the cylinder opposite to the pump with a port to connect the pump cylinder with the reservoir; and a tube extending longitudinally of the reservoir with its ends adjacent the side and opposite ends thereof and connected to the port in the laterally extended part of the pump to revolve on an axis longitudinally of the reservoir, for the purpose specified.

8. A syringe, comprising a cylinder having an extension of reduced width along one side thereof; pumping mechanism immovably mounted in the extended portion of the reservoir connected to the reservoir outlet; and a suction inlet tube connected to the pumping mechanism extending longitudinally of the reservoir and revolvable through a complete circle on an axis extending longitudinally of the reservoir without participating movement of the pumping mechanism, for the purpose specified.

9. A syringe comprising a cylinder having an extension of reduced width along one side thereof; a pump chamber immovably mounted in said extended portion connected to the reservoir outlet and having inlets in lateral projections adjacent opposite ends; valves in said inlets opening into and closing outward from said chamber; a piston to reciprocate in said chamber; and an intake 60 tube in fluid connection with said inlets to extend longitudinally of the reservoir and revolve through a complete circle on an axis extending longitudinally of the reservoir, for the purpose specified.

65 10. A syringe comprising a cylinder

having an extension of reduced width along one side thereof; a piston chamber immovably mounted in said extended portion connected to the reservoir outlet and having inlets in lateral projections adjacent opposite ends, one of said projections being adjacent one end of the reservoir and having a port opening into the reservoir; a piston to reciprocate in said chamber; a tube in the extended portion of the reservoir to connect the inlets in the piston chamber projections in fluid connection; and a tube extending longitudinally of the reservoir with its ends lying adjacent the side and opposite ends of the reservoir and connected to the port in the one piston chamber projection to revolve through a complete circle on an axis extending longitudinally of the reservoir, for the purpose specified.

11. In a syringe, the combination of a liquid carrying reservoir having an extension of reduced width along one side thereof; a piston chamber located in said extended portion of the reservoir; a piston to reciprocate in said chamber; and an intake tube to said piston chamber from the reservoir located at one side of the piston chamber and supported to rotate through a complete circle on an axis longitudinally of the reservoir and adapted to assume a position below its axis of rotation without participating movement of the piston chamber and unobstructed in its movement by the piston chamber in all positions thereof.

12. In a syringe, a liquid carrying reservoir; a piston chamber in said reservoir at one side thereof; a piston to reciprocate in said chamber; and an intake to the piston chamber from the reservoir to lie contiguous the side of the reservoir and rotatable on an axis longitudinally of the reservoir and adapted to assume variable positions in the reservoir around its axis of rotation without participating movement of the piston chamber and unobstructed in its movement by the piston chamber in all positions thereof.

13. In a syringe, a liquid carrying reservoir having an extension of reduced width along one side thereof; a piston chamber located in said extended portion of the reservoir; a piston to reciprocate in said chamber; and an intake to said piston chamber having inlets from opposite ends of the reservoir and rotatable through a complete circle on an axis longitudinally of the reservoir, and said intake being adapted to assume variable positions in the reservoir around its axis of rotation without participating movement of the piston chamber.

14. In a syringe, a liquid carrying reservoir having a piston chamber therein located at the side thereof; a piston to reciprocate in said chamber; an intake to said piston chamber having inlets from opposite ends of the reservoir rotatable through a com-

plete circle on an axis longitudinally of the reservoir and adapted to assume variable positions in the reservoir without participating movement of the piston mechanism; and valve mechanism operable to shut off one of the inlets to the intake from the reservoir when the other is open to the reservoir, for the purpose specified.

15. A fire extinguisher comprising a cylindrical pump having inlets to opposite ends thereof; a tube having inlets to opposite ends supported by the pump in fluid communication with the inlets thereto and to revolve through a complete circle without participating movement of the pump; and a reservoir having an outlet in which the pump with the connected tube is mounted at

the side thereof with the pump in communication with the outlet of the reservoir for the purpose specified.

16. A syringe comprising a reservoir having an outlet; pumping mechanism immovably mounted in the reservoir; a tube in communication with the pumping mechanism and reservoir, said tube extending longitudinally of and having inlets from opposite ends of the reservoir and supported to have revolving movement through a complete circle without like participating movement of the pumping mechanism; and valve mechanism operable to shut off communication between said tube and the reservoir outlet through the pumping mechanism.

GEO. T. PEARSONS.
